FIG. 1 is a perspective view of a container for holding a flexible coffee bag illustrating my new design;
FIG. 2 is a front elevational view of the design of FIG. 1;
FIG. 3 is a back elevational view of the design of FIG. 1;
FIG. 4 is a left side elevational view of the design of FIG. 1;
FIG. 5 is a right side elevational view of the design of FIG. 1;
FIG. 6 is a top plan view of the design of FIG. 1;
FIG. 7 is a bottom plan view of the design of FIG. 1;

FIG. 8 is a perspective view of an alternative embodiment of a container for holding a flexible coffee bag illustrating my new design;

FIG. 9 is a front elevational view of the design of FIG. 8;

FIG. 10 is a back elevational view of the design of FIG. 8;

FIG. 11 is a left side elevational view of the design of FIG. 8;

FIG. 12 is a right side elevational view of the design of FIG. 8;

FIG. 13 is a top plan view of the design of FIG. 8; and,

FIG. 14 is a bottom plan view of the design of FIG. 8.

The broken lines represent portions of the structure that form no part of the claim.
